UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A BASKET.

51,308.

Specification for Design.

Patented Sept. 25, 1917.

Application filed June 30, 1917. Serial No. 178,041. Term of patent 14 years.

To all whom it may concern:

Be it known that I, ANDREW J. SANFORD, a citizen of the United States, residing at Newark, Ohio, have invented a new, original, and ornamental Design for a Basket, of which the following is a specification, reference being had to the drawing, in which—

Fig. 2 is an end elevation, and

Fig. 3 is a top plan of a basket embodying the design.

I claim:

The ornamental design for a basket as shown.

ANDREW J. SANFORD.
